UNITED STATES PATENT OFFICE

ARDON K. BARTON, OF BLUE RIDGE SUMMIT, PENNSYLVANIA

FLUSH-TANK VALVE

Application filed April 5, 1930. Serial No. 441,993.

This invention relates to flush tanks such as are used in water closets and has special reference to means for siphoning the water from the tank to the bowl.

One important object of the invention is to provide a novel general construction of siphon for this purpose.

A second important object of the invention is to provide an improved arrangement of 10 siphon having novel means for releasing the air in the bell used herewith thus providing for rapid flushing.

A third important object of the invention is to provide a novel construction of siphon 15 having a gas seal to prevent passage of air from the bowl into the tank when the tank is full.

With the above and other objects in view, the invention consists in general of certain 20 novel details of construction and combinations of parts hereinafter more fully described, illustrated in the accompanying drawing and specifically claimed.

In the accompanying drawing like characters of reference indicate like parts in the several views and:

Figure 1 is a section through one end of a tank showing the device in position therein;

Figure 2 is a vertical section through the 30 siphoning device;

Figure 3 is a detail section similar to Figure 2 with the outer casing omitted and showing a modification of the invention.

As here shown, there is provided a tank 10 of ordinary construction having the siphoning device located therein.

In the form shown in Figure 2, this siphoning device includes a nipple 11 in the bottom 40 of the tank 10 and secured thereto by a nut 12. This nipple is for connection of the usual closet L (not shown). At one side this nipple is extended and is made hollow to provide an air chamber 13 from whence a pipe 14 extends up above the water level 15 in the tank.

A housing 16, closed at the top and extending above said water line is fixedly supported 45 on the flange of the nipple by legs 17 so that water may have free access to the interior. The upper part of the nipple is shouldered

50 inwardly to provide a reduced opening

through which fits an inner fixed siphon tube 18 having an outer member 19 fixed by its bottom edge around the upper part so as to provide a channel 20. In this channel 20 fits the inner wall 21 of a double walled bell which has an outer wall 22 surrounding the tube 19 in spaced relation thereto. The walls 21 and 22 are connected at their upper ends by a frusto-conical annular closure 23 which supports an inverted frusto-conical annular plate 24 the inner edge of which overhangs the opening of the tube 18.

Pivoted at its middle portion to a lug 25 projecting from one of the legs 17 is a lever 26 which has its inner end connected to the 55 bottom of the wall 22. Extending through the wall of the tank 10 above the water line is an operating lever 27 having its inwardly projecting end connected by a wire 28 to the remaining end of the lever 25.

In operation, the tank is normally full and the bell is in the dotted line position of Figure 2. To flush the closet, the outer end of the lever 27 is depressed which pulls this bell down until the water flows over the guide plate 24 into the tube 18 and starts siphonic action. This action draws, by aspiration, the air out from between the walls 21 and 22 and the channel 20 so that the bell drops to its lowest position as shown in Figure 2 and the 70 tank is rapidly emptied. When the tank is empty, the space between the walls 21 and 22 again fills with air so that, as the water rises in the tank through the usual inlet pipe (not shown) the bell will lift due to the trapped 80 air and assume its normal position.

In the form shown in Figure 3, the tube, 85 18 is replaced by a tube 29 double walled at its upper part, the outer wall being indicated at 30. The space between the body of the tube and this wall is closed at the top as at 31. The bell of Figure 2 is replaced in this form by a bell having an inner wall 32 and an outer wall 33 connected at their top edges by an inverted frusto-conical plate 34. The 90 inner wall has at its bottom an inwardly extending flange 35 from the inner edge of which rises a wall 36 which lies between the tube body 29 and the wall 30. Also the bell is provided with an intermediate partition 100

37 connected at its top by a plate 38 to the inner wall 32 of the bell.

The other arrangements are the same as in the first form and the operation is likewise the same, this form having a double air trap so that the flotation is increased.

There has thus been provided a simple and efficient device of the kind described and for the purpose specified.

10 It is obvious that changes may be made in the form and construction of the invention without departing from the principles thereof. It is not, therefore, desired to confine the invention to the exact form herein shown and described, but it is desired to include all such as come within the scope claimed.

Having thus described the invention, what is claimed is:-

20 1. A siphoning device for toilet tanks including a nipple, a siphon tube projecting upwardly from the nipple and having a channel surrounding its upper end and opening upwardly, a double walled bell having its inner wall in said channel and its outer wall 25 extending around the tube in spaced relation thereto, a closure connecting the top of said walls, an inverted frusto-conical guide plate carried by the upper end of the bell and overhanging the tube, and means to depress the 30 bell against floatative action of air thereon.

25 2. A siphoning device for toilet tanks including a nipple, a siphon tube projecting upwardly from the nipple and having a channel surrounding its upper end and opening upwardly, a double walled bell having its inner wall in said channel and its outer wall 35 extending around the tube in spaced relation thereto, a closure connecting the top of said walls, an inverted frusto-conical guide plate carried by the upper end of the bell and overhanging the tube, means to depress the bell 40 against floatative action of air thereon, said nipple being in spaced relation to the lower end of the tube, an air chamber communicating with the space between the tube and nipple, and a pipe leading from said air chamber 45 and terminating above the normal water level of the tank.

30 3. A siphoning device for toilet tanks including a nipple, a siphon tube projecting upwardly from the nipple and having its upper end provided with an outer tube wall connected to the body of the tube at its top by a closure plate, a double walled bell having 35 the space between its walls closed at the top, a flange extending inwardly from the bottom of the inner wall and provided at its inner edge with an upstanding wall positioned between the tube body and the outer tube wall, and a partition extending up from the bottom 40 of the bell between its walls and connected at its top to the inner bell wall by a closure plate.

65 In testimony whereof I affix my signature.
ARDON K. BARTON.
